RECORD BLANK SUPPORTING ARBOR AND ASSEMBLY DEVICE

Lawrence E. Dettle, Chicago, Ill., assignor to
Rock-Ola Manufacturing Corporation, Chicago,
Ill., a corporation of Delaware

Application June 27, 1941, Serial No. 400,137

11 Claims. (Cl. 91—60)

This invention relates in general to the manufacture of record blanks for the recording of sound tracks, and more particularly to novel means for expediting the assembling and supporting of record blanks or matrices to facilitate the subsequent coating thereof.

In the manufacture of a record blank, a matrix or base disc of cardboard, fiber, sheet metal, or any other desired material is coated with a well-known lacquer or other suitable compound adapted to subsequently receive sound recording impressions. One method of accomplishing this result is to mount a plurality of record blanks or matrices concentrically and in spaced relationship on a shaft or arbor, dip the blanks edgewise into a predetermined depth into the coating compound, rotate the blanks to cover all but their undipped central portions with the compound, and then to dry or bake the coating compound thereon. Such a method and apparatus for performing the same is disclosed in the co-pending application for United States Letters Patent of David C. Rockola, Serial No. 382,951, filed March 12, 1941.

A principal object of the instant invention is to expedite the assembly and retention of a plurality of record blanks or other disc-like members in concentric and axially spaced relationship relative to each other, thus saving time and labor in the above-described coating process or any other one similar thereto.

Another important object of the invention is the provision of a novel arbor for supporting and rigidly retaining a plurality of disc-like members in spaced relationship thereon.

A further important object of the invention is the provision of a device for peripherally and individually supporting a plurality of record blanks, or other disc-like members, and a plurality of cylindrical spacer members in axially aligned and alternate relationship to enable such an arbor to be passed longitudinally through central apertures in said members, thereby facilitating the assembly on, and the removal from, the arbor of the record blanks, while eliminating all handling of the spacer members interposed therebetween.

Another object of the invention is the provision of record blank supporting means in such a device which may readily be adjusted to accommodate record blanks of different diameters.

A further object of the invention is the provision of individual supporting means for the spacer members in such a device which are movable to permit axial adjustment of the spacers to facili-

tate the placing of record blanks therebetween.

Another object of the invention is the provision in such a device of means readily engageable with, and disengageable from, the arbor to enable rapid securing or tightening of the record blanks and spacer members thereon and loosening of the same therefrom.

Numerous other objects and advantages of the invention will be apparent as it is better understood from the following description, which, when taken in connection with the accompanying drawings, discloses a preferred embodiment thereof.

In the drawings,

Figure 1 is a front elevation of an arbor and assembly device embodying the features of the invention, with part of the means for engaging and rotating the arbor record blank retaining member shown in section;

Figs. 2, 3 and 4 are transverse vertical sections taken substantially on the lines 2—2, 3—3 and 4—4, respectively, of Fig. 1;

Fig. 5 is an enlarged, detail vertical section taken longitudinally of the arbor in its position of Fig. 1 and with parts thereof broken away; and

Fig. 6 is an end elevation of the upper part of one of the spacer supporting members.

Referring more particularly to the drawings, reference numerals 11 and 12 indicate in general, respectively, an arbor and an assembly device embodying the features of the invention, which are designed to facilitate the handling of disc-like members 13, such as record blanks, or matrices, and members 14 for properly spacing the latter from each other on the arbor. The arbor 11 comprises a main portion having a shoulder 15 formed intermediate its ends, and a reduced portion 16 terminating in a pointed end 17 and threaded on its outer surface adjacent thereto. The end of the arbor 11 opposite the pointed end 17 is provided with a hub portion 18 (Fig. 1), and a suitable roller 19 is rotatably mounted in any desired manner adjacent this outer hub portion 18. A sprocket wheel 21 is rigidly secured to the arbor 11 adjacent the roller 19.

The disc-like members 13 and spacers 14 are mounted upon the reduced portion 16 of the arbor in a manner to be later more fully described, and are rigidly held against the shoulder 15 by means of a retaining member 22 which is provided with a tapped bore adapted to engage the threaded end portion of the reduced part 16 and forming a part of the arbor. The retainer member 22 (Fig. 1), terminates at its outer end in a hub

portion 23 which is similar to the hub portion 18 at the other end of the arbor. The retaining member 22 is also provided with a roller 24 which is similar to the roller 19.

When a plurality of record blanks 13 have been mounted upon the arbor 11 in the manner illustrated in Fig. 1, they are held thereon in position for the subsequent dipping and drying steps of the process hereinbefore described. In this process, as disclosed in the copending application referred to, the hub portions 18 and 23 of the arbor are engageable with suitable conveyor means, and the rollers 19 and 24 function to support the arbor and the record blanks carried thereby during the process of coating and drying the latter. At the same time, the sprocket wheel 21 periodically engages suitable chain or rack means (not shown herein) for rotating the arbor and the record blanks to effect proper coating thereof.

While the present invention is directed to the novel form of supporting arbor above described, it also includes the assembly device 12 for expediting the mounting upon and removal from the arbor of the disc-like members or record blanks 13 and spacer members 14. The assembly device 12 comprises a supporting frame which includes a pair of end plates 25 upstanding from and secured in any desired manner to a suitable base member 26. If desired, the base member 26 may be mounted upon rollers or other suitable supporting means which are not illustrated in the instant drawings, since they do not form an essential part of the invention. The upper ends of the end plates 25 are each provided with a pair of angularly disposed series of apertures 27 (Fig. 2), spaced a predetermined distance from each other in a manner to be more fully described hereinafter. A pair of longitudinally extending rods 28 are removably positioned in selected ones of the apertures 27 for the purpose of peripherally supporting the disc-like members or record blanks 13.

Adjacent the base 26 (Figs. 1 and 2), a pair of tie-rods 29 are provided which extend longitudinally of the assembly device 12 and through the end plates 25 to which they are secured in any suitable manner. A plurality of vertically extending spacer member supports 31 are slidably mounted upon the tie-rods 29 at their lower ends. Longitudinal movement of the supporting members 31 on the rods 28 is limited by adjustable stop members 32 and 33 (Fig. 1), threaded through suitable apertures in the respective end frames 25. The stop members 32 and 33 cooperate with the outside supports 31 intermediate the tie-rods 29, and these portions of all of the supports 31 are provided with recesses 34 to facilitate spreading apart of the supporting members. The upper end of each of the supporting members 31 terminates in a yoke portion 35 (Figs. 2, 5 and 6), having a semi-circular recess 36 in the upper surface thereof.

Each member 31 is adapted to support one of the spacer members 14 at its upper end. As best shown in Fig. 5, each of the spacer members 14 is provided with a pair of circumferential flanges 37 which define the side walls of an annular groove 38. The recesses 36 in the upper end of the yoke portion 35 of each of the supporting members 31 is so dimensioned relative to the spacer members 14 as to slidably embrace the inner surface of the groove 38. Each of the supporting members 31 is thus adapted to maintain one of the spacer members 14 thereon at a definite vertical posi-

tion, while permitting lateral movement of the spacer member relative thereto, such movement being limited by the flanges 37. Each of the spacer members 14 is provided with a central bore or aperture 39 (Fig. 5), and when mounted upon the supporting members 31, the bores of all of the spacer members will be maintained in alignment with each other.

The apertures 27 in each series are so spaced relative to each other that when the rods 28 are disposed therein, the distance from the outer surface of the rods on the center line of the apertures to the center of the recesses 36 in the upper ends of the supporting members 31 will be equal to the radius of different standard sizes of record blanks. Thus, as will be seen in Fig. 2, the rods 28 are shown as extending through the second from the top aperture 27 in each series thereof. In such position, the rods 28 are adapted to peripherally support record blanks 13 having an 8-inch diameter so that the usual central apertures 41 provided therein (Fig. 5), will be aligned with the bores 39 of the spacer members 14 mounted upon the supporting members 31. Similarly, the upper apertures 27 are so positioned that when the rods 28 extend therethrough, 6-inch record blanks will be supported thereby in like manner with their central apertures in alignment with the bores 39 of the several spacer members 14. Any desired number of such apertures 27 may be provided, the arrangement illustrated in Fig. 2 being intended to selectively accommodate records of 6, 8, 10, 12 or 16-inch diameter.

When it is desired to assemble a plurality of record blanks 13 and spacer members 14 in alternate relationship upon an arbor 11, the spacers 14 are first disposed or set upon the upper ends of the supporting members 31. The record blanks 13 are then inserted between the respective spacer members 14 so as to rest upon the rods 28, the latter having been positioned in the proper apertures 27 corresponding with the diameter of the particular blanks 13 being handled. In order to facilitate such positioning of the record blanks 13, the supporting members 31 may first be spread slightly apart from each other by moving the lower ends thereof along the tie-rods 29. The recesses 34 may expedite such spreading of the supporting members 31, and the stop members 32 and 33 will limit movement thereof to prevent spacing of the members 14 to such an extent as to result in misalignment of the record blanks. In other words, the spacer members 14 function to retain the record blanks 13 in substantially vertical position on the rods 28, and spacing thereof at too great a distance might result in the central apertures of the members being thrown too far out of alignment.

The reduced portion 16 of the arbor 11 is then passed through the aligned apertures 41 and 39 until all of the members 13 and 14 are in position thereon, the pointed end 17 being provided to facilitate such action. The left-hand stop member 32 (Fig. 1), is so adjusted that when the arbor 11 has been moved sufficiently far to the right to place the shoulder 15 in contact with the end record blank 13, the sprocket wheel 21 will be substantially aligned with the left-hand end plate 25.

Mounted at the upper end of this end plate 25 (Figs. 1 and 3), are a pair of chains 42 and 43 which are pivotally connected in any suitable manner at one end to the end plate, as indicated at 44 in Fig. 3. After the arbor 11 has been posi-

tioned in the manner hereinbefore described, it is supported through the intermediary of the members 13 and 14 by the rods 28 and members 31. The chain 42 is then swung upwardly from normal or inoperative position to engage with the sprocket wheel 21, as shown in broken lines in Fig. 3. In this position, the chain 42 will prevent rotation of the arbor in a clockwise direction, as viewed from the right-hand end of the assembly device 12 and as seen in Fig. 3.

A bracket 45 is mounted in any suitable manner upon the outer surface of the right-hand end plate 25 (Fig. 1), to support a bearing or trunnion block 46. Slidably and rotatably supported by the bearing 46 is a shaft 47 having a crank 48 secured to the outer end thereof. At its inner end, the shaft 47 terminates in a recessed chuck 49 having a bore of greater diameter than the hub portion 23 of the arbor retaining member 22. The inner surface of the end wall of the chuck 49 is provided with an outwardly extending rib or key 51 (Figs. 1 and 4), which is adapted to engage a slot or keyway 52 formed in the outer end surface of the hub portion 23. The chuck 49 is also provided with a longitudinal slot 53 within which is disposed the forward end of a latching pawl 54. The pawl 54 is pivotally connected to the chuck 49 intermediate its ends by a pin 55, and is provided at its outer end with a depending rod 56. The rod 56 extends through a suitable aperture in the shaft 47, and is provided with an enlarged head portion at its lower end to limit upward movement relative to the shaft. Surrounding the rod 56 and interposed between the latch 54 and the shaft 47 is a spring 57 which functions to urge the forward or nose end of the pawl 54 downwardly.

With this arrangement, after the arbor 11 has been inserted through the several members 13 and 14, the retaining member 22 is screwed upon the outer threaded end of the reduced portion 16. In order to tighten the retaining member 22 sufficiently to rigidly secure the record blanks 13 on the arbor, the shaft 47 is moved inwardly from its normal position (which is shown in broken lines in Fig. 1) to engage the key 51 in the keyway 52. The pawl 54 will then automatically function under the influence of the spring 57 to retain the chuck 49 in engagement with the member 22. Rotation of the crank 48 will then rotate the retaining member 22 to furnish the desired tightening thereof. At the same time, the chain 42 will prevent similar rotation of the arbor 11. In this manner, the disc-like members or record blanks 13 may be rapidly mounted upon the arbor 11.

After the record blanks have been coated as described hereinbefore, the assembly device 12 may be employed to facilitate removal thereof from the arbor 11. In such operation, the arbor and its supported members 13 and 14 are repositioned upon the device 12, as shown in Fig. 1. The chain 43 is then swung upwardly into its operative position, as shown in broken lines in Fig. 3, to engage the sprocket wheel 21. The chuck 49 having been engaged with the retaining member 22 in the manner hereinbefore described, rotation of the crank 48 in a counter-clockwise direction, as viewed from the right end of Fig. 1, will cause removal of the retaining member 22 from the arbor. It is then only necessary for the operator to disengage the chain 43 and remove the arbor 11 endwise from the members 13 and 14. The members 13 may then be removed while the spacer members 14 will not be disturbed, but

will be left on their supporting members 31. In this operation the supporting members may be spread longitudinally of the rods 29 if desired.

An important feature of this arrangement is the fact that handling of the spacer members 14, after they have once been employed, is entirely eliminated. After the completed record blanks 13 have been removed from the assembly device 12, uncoated blanks may then be positioned on the rods 28 between the spacer members, and the arbor member again passed through the several apertures 31 and 39.

It is thought that the invention and many of its attendant advantages will be understood from the foregoing description, and it will be apparent that various changes may be made in the form, construction and arrangements of the parts without departing from the spirit and scope of the invention or sacrificing all of its material advantages, the form hereinbefore described being merely a preferred embodiment thereof.

I claim:

1. In a device of the class described, means for supporting a plurality of centrally apertured disc-like members in spaced relationship to each other, means for supporting centrally apertured spacer members between said disc-like members, whereby the apertures in all of said members will be aligned with each other to enable passage of an arbor therethrough, means rotatably engageable with said arbor to retain said members thereon, and means removably engageable with said retaining means for rotating the same relative to said arbor.
2. In combination with an arbor adapted to support a plurality of centrally apertured disc-like members and spacer members in alternately arranged relationship and having means for securing the same thereon, an assembly device, comprising means for supporting said members to maintain the central apertures thereof in alignment to enable said arbor to be passed therethrough while permitting relative movement of said members longitudinally of said arbor, and means removably engageable with said securing means to actuate the same to prevent relative movement between said members and said arbor.
3. A device to facilitate the assembly of centrally apertured disc-like members and spacer members in alternate relationship on an arbor, comprising a supporting frame, means mounted on said frame for supporting said spacer members in spaced relationship to each other to enable placing of said disc-like members therebetween, and means mounted on said frame for removably supporting said disc-like members to maintain the central apertures therein in alignment with those of said spacer members to receive said arbor, and to enable removal of said arbor therefrom and subsequent removal only of said disc-like members without removing said spacer members from their supporting means.
4. A device to facilitate the assembly of centrally apertured disc-like members and spacer members in alternate relationship on an arbor, comprising a supporting frame, means mounted on said frame for peripherally supporting said disc-like members to maintain their central apertures in alignment, and means movably mounted on said frame for individually supporting said spacer members with their central apertures in alignment with those of said disc-like members to enable said arbor to be passed therethrough.
5. A device to facilitate the assembly of centrally apertured disc-like members and spacer

members in alternate relationship on an arbor having means for securing said members thereon, comprising a supporting frame, means mounted on said frame for supporting said members to maintain the central apertures therein in alignment to enable said arbor to be passed therethrough, said members being mounted on said supporting means for movement relative to each other longitudinally of said arbor, means mounted on said frame for removably engaging said securing means to actuate the same to secure said members in said arbor, and means mounted on said frame and removably engageable with said arbor to prevent movement thereof during actuation of said securing means.

6. An arbor for supporting a plurality of centrally apertured disc-like members and spacer members in alternately arranged relationship, comprising a shoulder portion intermediate the ends thereof, an outwardly threaded reduced portion formed integrally with said shoulder portion and adapted to be passed through the apertures in said members, an internally threaded retaining member engageable with said reduced portion to force and retain said members against said shoulder portion, and rollers mounted adjacent said shoulder portion and on said retaining member, respectively, to support said arbor.

7. An arbor for supporting a plurality of centrally apertured disc-like members and spacer members in alternately arranged relationship, comprising a shoulder portion intermediate the ends thereof, an outwardly threaded reduced portion formed integrally with said shoulder portion and adapted to be passed through the apertures in said members, an internally threaded retaining member engageable with said reduced portion to force and retain said members against said shoulder portion, rollers mounted adjacent said shoulder portion and on said retaining member, respectively, to support said arbor, hub portions formed adjacent said rollers for engagement by suitable conveying means, and a sprocket wheel mounted on said arbor for rotating the same relative to said rollers.

8. A device to facilitate the assembly of centrally apertured record blank members and spacer members in alternating relationship on an arbor, comprising a supporting frame, means mounted on said frame for supporting said spacer members in spaced relationship to each other to enable placing of said record blanks therebetween, and means adjustably mounted on said frame for supporting groups of record blanks of

the same diameter and adjustable to support groups of different diameter so as to maintain the central apertures therein in alignment with those of said spacer members to enable said arbor to be passed therethrough, said last means comprising rods engageable in different apertures in said frame and extending longitudinally thereof for supporting other groups of record blanks of different diameters at circumferentially spaced 10 points on the periphery thereof all of the records in each of said groups having the same diameter.

9. A device to facilitate the assembly of centrally apertured disc-like members and spacer members in alternate relationship on an arbor, comprising a supporting frame, means mounted on said frame for peripherally supporting said disc-like members to maintain their central apertures in alignment, tie-rods extending longitudinally of said frame, and a plurality of spacer member supports slidably mounted upon said rods adjacent their lower ends and adapted to peripherally engage said spacer members at their upper ends to individually support the same independently of said disc-like members with the central apertures thereof in alignment with those of said disc-like members.

10. In combination with cylindrical members having central bores for engagement with an arbor, an assembly device, comprising a plurality of vertically disposed members slidably mounted adjacent their lower ends for limited horizontal movement relative to each other and terminating at their upper ends in yoke-shaped portions engageable with the outer surfaces of said cylindrical members to individually support the latter to maintain said bores in horizontal alignment.

11. An arbor for supporting a plurality of centrally apertured disc-like members and spacer members in alternately arranged relationship, comprising a shoulder portion intermediate the ends thereof, an outwardly threaded reduced portion formed integrally with said shoulder portion and adapted to be passed through the apertures in said members, an internally threaded retaining member engageable with said reduced portion to retain said members against said shoulder portion, a roller mounted on said retaining member, hub portions formed on said shoulder portion and said retaining member for engagement by suitable conveying means, and a sprocket wheel mounted on said arbor for rotating the same.

LAWRENCE E. DETTLE.
